GOTTHELF M. SEIDEL, OF EASTHAMPTON, MASSACHUSETTS.

BOTTLE-CAP.

1,259,143.

Specification of Letters Patent. Patented Mar. 12, 1918.

Application filed May 7, 1917. Serial No. 166,958.

To all whom it may concern:

Be it known that I, GOTTHELF M. SEIDEL, a citizen of the United States, residing at Easthampton, in the county of Hampshire and State of Massachusetts, have invented 5 a new and useful Bottle-Cap, of which the following is a specification.

My invention relates to stoppers or caps for milk and other bottles, and has for its 10 object to provide an article for the purpose stated which will be simple in construction, inexpensive to make, and sanitary in use.

Milk and other bottle caps must necessarily fit very tightly into the bottles in order to insure a perfect seal, as well as secure 15 them against accidental dislodgment. Because of this fact, it is difficult to remove such caps from bottles unless a tool is used for the purpose, or the caps are provided 20 with individual means for removing the same. The employment of tools which puncture the caps is objectionable on sanitary grounds. Numerous methods have been tried to provide a cap with pulling 25 means. Among others, small bits of metal, cloth or paper have been attached to the caps to form tabs for pulling the same, but the cost of the material and the labor of attaching such tabs to caps in a reasonable, 30 substantial and sanitary manner have been found to be far in excess of what an article of this nature would warrant, and such methods have been found to be too costly 35 for general use.

Attempts have been made to overcome 40 this objection by forming the cap with an outwardly extending lip to serve as a means to pull the cap from the bottle. Such lips have been found impracticable for general use, because they were entirely insufficient 45 in strength to withstand the strain to which they must be subjected, very often breaking under the strain, leaving the cap worse off than if no means had been provided in the first instance.

To produce a cap that embodies the requisite features, viz: convenience, the absence of tools, and the cost no greater than the ordinary caps in general use, I cut the cap 50 in a manner to form a key, or tab, or lip, the incisions extending from the outer periphery of the cap toward and near to the center thereof, and having a depth less than the thickness of the cap. By this construction, that portion of the key or tab which bears the pulling strain in lifting the cap

from the bottle is of a diameter and size to withstand the strain without breaking.

In the drawing:

Figure 1 is a top plan view of the bottle 60 cap.

Fig. 2 is a bottom plan view.

Fig. 3 is a vertical section of the neck portion of a milk bottle showing in elevation the cap applied thereto and the tab torn 65 up from the cap in position for removing the latter.

Fig. 4 is a sectional view on an enlarged scale, showing the cap in the same position as in Fig. 3.

Fig. 5 is a sectional view taken on the line 5-5 of Fig. 1.

Fig. 6 is an edge elevation looking at the edge of the cap from which the tab is formed, showing the tab torn up from the 75 cap.

Fig. 7 is a sectional view of a bottle similar to Fig. 3, showing a cap in its closed position.

Similar reference numerals designate corresponding parts in all the figures of the drawing.

Referring to the drawing, 8 designates the body of the cap, which is made of cardboard, pulp board, or other suitable material, preferably of laminated formation, that is to say, formed of superimposed layers, though any material which will split or peel will answer the purpose. Projecting from the periphery of the cap and integral 85 therewith is an ear 9 which is transversely scored on its under face at 10, so as to facilitate the bending up of the tab or lip when the cap is applied to a bottle, (Fig. 7). The scoring is coincident with and follows the 90 curved outer edge of the cap, as shown in Fig. 1, so that the curve of the cap is not interrupted at the bending line when the tab is bent up.

Diverging inwardly from the side edges 100 of the ear are incisions or slits 11, which terminate well into the body of the cap near to the center, so that their terminals are spaced quite a distance apart. These incisions or slits penetrate the greater part of the thickness of the cap, but do not pass entirely through the bottom layer, as shown in Fig. 2, so as to leave the lower face 12 of the cap intact and unbroken when the tab or lip 13 is torn up from the same, thereby preventing 105 any foreign matter from entering the bottle 110 when the cap is re-applied. The exact shape

of the tab or lip 13 defined by the slits or incisions is not important. The shape shown has been found to be the most satisfactory from practical experience, the important consideration being that the tab or lip is of a materially greater width at the end where it connects with the cap than at its outer or free end.

10 The normal position of the ear when the cap is applied is shown in Fig. 7, the ear bending upwardly when the cap is pressed down and extending at right angles in a position to be readily grasped by the fingers in removing the cap.

15 From the foregoing description taken in connection with the drawing, it will be seen that upon taking hold of the ear and giving it a gentle upward pull, it will break entirely loose from the periphery of the cap, 20 (Figs. 3, 4 and 6, this being due to the score line 10), said ear carrying with it the material between the incisions 11, which peels away from the bottom layer, to a point where said incisions terminate, the bottom 25 layer remaining unbroken, thereby forming a pull or tab having a base much wider, and therefore much stronger, than the ear itself. By pulling on this newly-formed tab it will be understood that, no matter how snugly 30 the cap may fit the bottle, it will be removed without the tab becoming torn from the cap. The ease with which the cap may be dislodged or re-applied is augmented by the greater flexibility of the part from which 35 the tab has been formed. The security of the seal is no wise affected, while the manufacturing and material costs are not increased by reason of the improvement in which the tab is a homogeneous part of the 40 cap.

The cap may be made of any suitable material or size, and changes in the shape of the ear and tab may be made within the scope of the appended claims without de- 45 parting from the spirit of this invention.

What I claim is:

1. A bottle cap having an integral ear

projecting from its periphery and having the same thickness as the cap, and a tab defined by a pair of incisions starting from 50 the periphery of the cap at the base of said ear and diverging inwardly toward the center of the cap, said incisions after leaving the periphery of the cap being spaced inwardly from said periphery, said tab having 55 a greater width than said ear but of less width than the cap, and the thickness of the tab being less than the thickness of the cap, whereby a means for removing the cap is provided, which means is an integral part 60 of the cap.

2. A bottle cap having pulling means forming a homogeneous part thereof and consisting of an ear projecting from the periphery of the cap and equal in thickness thereto, said ear being transversely scored on the under side in line with the periphery of the cap, and a tab defined by a pair of incisions, which incisions are of less depth than the thickness of the cap and lead inwardly from the periphery of the latter, joining with the sides of the ear and diverging inwardly toward the center of the cap, said incisions after leaving the periphery of the cap being spaced from said periphery, thereby providing a tab with a wide base, the width of the base of the tab being materially greater than the width of the ear, but less than the width of the cap, whereby upon bending the ear upwardly 70 and pulling thereon it may be torn loose from the edge of the cap, carrying with the ear the portion of the cap between the incisions, which portion peels away from the remaining portion thereof and constituting 75 a pulling tab of sufficient strength to withstand breakage.

In testimony that I claim the foregoing as my own, I have hereto affixed my signature in the presence of two witnesses.

GOTTHELF M. SEIDEL.
